UNITED STATES PATENT OFFICE.

JOHN B. GILLIE, OF NORTH TONAWANDA, NEW YORK.

PORTABLE PLANING-MACHINE.

No. 806,794.

Specification of Letters Patent.

Patented Dec. 12, 1905.

Application filed October 2, 1903. Serial No. 175,448.

To all whom it may concern:

Be it known that I, JOHN B. GILLIE, a citizen of the United States, residing at North Tonawanda, in the county of Niagara and 5 State of New York, have invented certain new and useful Improvements in Portable Planing-Machines; and I do hereby declare the following to be a full, clear, and exact description of the same, such as will enable others skilled in the art to which it appertains to make and use the same.

This invention relates to portable planing-machines, and is particularly designed for planing valve-seats of marine engines, but 15 may be used generally, if desired.

The primary object of my invention is to provide a machine which can be quickly and conveniently applied to a marine engine located in a boat to plane the valve seat or 20 seats thereof.

Other objects are to provide an inexpensive, effective, and reliable planer which may be operated by hand or power, to provide means for adjusting the frame or guides of 25 the machine relative to the valve-seat to cause the cutting-tool to properly plane the latter, and to provide an extensible reciprocating carriage which can be adjusted to any size engine.

30 To these ends the invention consists of the new and novel construction, arrangement, and combination of parts, as will be herein-after described, and more particularly pointed out in the appended claims.

35 In the drawings, Figure 1 is a front elevation of my improved portable planer. Fig. 2 is a horizontal section taken on line W W, Fig. 1. Fig. 3 is an enlarged horizontal section taken on line X X, Fig. 1. Fig. 4 is an 40 enlarged horizontal section taken on line Y Y Fig. 1. Fig. 5 is a vertical section taken on line Z Z, Fig. 4.

45 Referring to the drawings in detail, like numerals of reference refer to like parts in the several figures.

The reference-numeral 1 designates part of an engine showing part of the cylinder 2, the valve-chamber 3, and the engine-frame 4. In the wall 5, located between the valve-chamber 50 and the cylinder, are the inlet and exhaust ports 6, and the outer face 7 of the said wall serves as a valve-seat for a slide-valve, as is common in steam-engines. The valve-casing is provided with an external flange 8, 55 having stud-bolts 9 secured therein, by means

of which and coacting nuts a plate or other suitable closure is affixed.

In applying my improved planing-machine to the engine the plate or closure just referred to is removed, and by means of suitable clamping-plates or keepers coöperating with the stud-bolts 9 the machine can be quickly and conveniently applied to the casting of the valve-chamber.

The planing-machine comprises two parallel vertical frame-bars 10, preferably cylindrical in cross-section, which extend from the floor 11 to a point above the upper edge of the valve-chamber. The said frame-bars are positioned on opposite sides and in advance of 65 the valve-seat and are held between stud-bolts on the upper and lower horizontal flanges, which stud-bolts serve, with the aid of keepers 12, to clamp the said bars to the valve-chamber at the four corners thereof. Each keeper 70 consists of two clamping-plates, between which and the stud-bolts above referred to the parallel frame-bars 10 are secured. The inner clamping-plate 13 of each keeper is slotted lengthwise, as at 14, and at each end 75 has a set-screw 15 passing therethrough, which set-screws are adapted to bear with their ends against the flanges of the valve-casing, and on turning said set-screws in either direction the said clamping-plate, which serves 80 as an adjusting-plate, can be moved toward and from the valve-chamber. The said adjusting-plates are carried on the stud-bolts, between which the frame-bars 10 are held.

The outer clamping-plate 16 of each keeper 85 is also provided with a longitudinal slot 17 to permit the same to be passed over the stud-bolts, and the said clamping-plates 16 are forced against said frame-bars by means 90 of nuts 18, screwed onto the projecting ends 95 of the said stud-bolts. By adjusting the inner plates 13 of the keepers the frame-bars 10 may be quickly adjusted with reference to the valve-seat, and the said bars may also be adjusted laterally between the clamping- 100 plates by loosening the outer plate.

19 designates an extensible reciprocating carriage which comprises two cylindrical cross-bars 20 and slide-heads 21, arranged for reciprocal movement on the frame-bars. 105 Each slide-head is provided with a vertical socket 22, which encircles one of the frame-bars and by means of which the reciprocating carriage is guided on said frame-bars, and two horizontal sockets 23, in which the cross- 110

bars 20 are adjustably held by set-screws 24, passing through the walls of the sockets and impinging against said cross-bars. This permits the frame-bars to be separated to any extent within certain limits, depending on the length of the cross-bars 20, which permits the said frame-bars to be quickly and conveniently adjusted.

25 designates the operating crank-shaft, which may be revolved manually or by means of power. The said shaft is journaled in adjustable bearings 26, secured to the frame-bars near their lower ends, and its outer ends are provided with similarly-disposed crank-arms 27. Pitmen 28 are secured with their lower terminals to crank-arms 27 and with their upper terminals to lateral extensions 29, formed on the slide-heads 21. On revolving the crank-shaft 21 the carriage is reciprocated vertically on the frame-bars through the medium of the said pitmen.

I have illustrated one form of power drive; but any other means for revolving the crank-shaft may be resorted to, if desired. I have 25 shown a bevel-gear 30, secured to the crank-shaft, which meshes with a bevel-gear 31, secured to a counter-shaft 32 having secured to its other end a spur-gear 34, which meshes with a pinion 35, secured to the main shaft 36, 30 having the belt-pulley 37 affixed thereon. The main shaft 36 and the counter-shaft 32 are journaled in bearings 38, supported in any suitable manner.

In many instances the space below the cylinder and between the engine-frame is taken up with the mechanism of the engine, and it is necessary to adjust the crank-shaft so as not to interfere with the said mechanism. This I do by forming the bearings 26 in two 35 sections, one section 39 being a securing-section secured to the frame-bars 10 and the other section 40 being a bearing-section adjustable on the securing-section. The front end of the securing-section is bifurcated, as 40 at 41, to receive a rearwardly-extending lug 42, having an aperture 43 formed therein. An adjusting-bolt 44 is passed through slots 45, formed in the bifurcated securing-section and through the aperture 43 and serves to 45 hold the two sections together in any adjusted relation. In this manner the crank-shaft can be moved away from the mechanism of the engine.

46 designates the tool-holder, which is 50 moved laterally intermittently on the cross-bars 20 of the reciprocating carriage. A cutting-tool 47 is provided which is adjustably secured to the tool-holder in any suitable manner and is designed to plane the 55 valve-seat on its upward movement. As is common in planers, the tool is inactive on its return stroke, and during such movement the tool-holder is moved laterally to bring the tool in line with the contiguous uncut 60 part of the valve-seat. The intermittent

lateral movement or feed of the tool is effected through the medium of the feed-screw 48, which is held from lengthwise movement in one of the slide-heads 21 and has threaded connection with the tool-holder 70 46. To one end of the said feed-screw a toothed wheel 49 is secured, and as the reciprocating carriage is moved upward said toothed wheel engages the under side of a hinged or pivoted dog 50 and deflects the 75 same, while on the downward movement of the carriage the said toothed wheel engages the upper side of said dog and is caused to revolve until the tooth engaging the dog clears the same. The pawl 51 is hinged to 80 an arm 51, held adjustable in any suitable manner to the valve-chamber.

Having thus described my invention, what I claim is—

1. In a portable planer adapted to plane 85 the valve-seat of an engine, the combination with stud-bolts projecting from the engine-casing, of an open frame comprising two vertical frame-bars adapted to be positioned between said stud-bolts, adjustable plates having each a longitudinal slot adapted to fit onto said stud-bolts and being located between said frame-bars and the valve-casing, set-screws passing through the adjusting-plate and serving to hold the latter any desired distance from the valve-casing, clamping-plates having each a longitudinal slot and being adapted to fit over said stud-bolts 90 and bear against the frame-bars, and securing-nuts engaging the ends of said stud-bolts 100 and serving to force said clamping-plate against the frame-bars to hold the same securely against the adjusting-plates.

2. In a portable planer adapted to plane 105 the valve-seat of an engine, the combination of two parallel frame-bars secured to the engine, slide-heads movable on said frame-bars, parallel rods connecting said slide-heads and being adjustable therein, a tool-holder movable on said parallel rods, a tool held adjustable on said tool-holder, means to reciprocate said parallel rods and attached parts, and feed mechanism to intermittently move said tool-holder on said parallel rods.

3. In a portable planer adapted to plane 115 the valve-seat of an engine, the combination of two parallel bars secured to the engine on either side and in advance of the valve-seat, slide-heads having each a vertical socket encircling said frame-bars and two horizontal 120 sockets in advance of said vertical socket, two parallel rods held in said horizontal sockets, a tool-holder carried on said parallel rods, a tool held adjustable on said tool-holder, means to reciprocate said parallel rods and attached parts, and mechanism to intermittently move the tool-holder on said parallel rods.

4. In a portable planer adapted to plane 125 the valve-seat of an engine, the combination 130

with stud-bolts projecting from the engine-casing, of an open frame comprising two vertical frame-bars adapted to be positioned between said stud-bolts, an adjustable clamping-plate between the casing and each of the frame-bars and having a longitudinal slot fitting onto said stud-bolts, said clamping-plate serving to adjust the frame-bars toward and from the engine-casing, a slotted clamping-plate lying outside of each frame-bar, and means for clamping the frame-bars between said clamping-plates.

5. In a portable planer adapted to plane the valve-seat of an engine, the combination with the frame-bars and a reciprocating carriage on said frame-bars, of bearings secured to said frame-bars and comprising securing portions held to said frame-bars and bearing portions adjustable on the securing portions, 20 a crank-shaft journaled in said bearing portions, and a pitman connecting said crank-shaft with the reciprocating carriage.

6. In a portable planer adapted to plane the valve-seat of an engine, the combination with the frame-bars and a reciprocating carriage on said frame-bars, of bearings adjustable on said frame-bars, each comprising a 25 socket-like securing portion held on the bars

and having a bifurcated front end and a bearing portion having a rearwardly-extending lug entering said bifurcated end of the securing portion and being adjustable therein, a crank-shaft journaled in said bearing portions, and a pitman connecting said crank-shaft with the reciprocating carriage. 30

7. In a portable planer adapted to plane the valve-seat of an engine, the combination with the frame-bars and a reciprocating carriage on said frame-bars, of bearings on said frame-bars, each comprising a securing portion adjustably secured to the frame-bars and having a slot therein and a bearing portion coöperating with said securing portion, a bolt passing through the bearing portion and the slot in the securing portion to render the bearing portion adjustable on the securing portion, 40 a crank-shaft journaled in said bearing portions, and a pitman connecting the crank-shaft with the reciprocating carriage. 45

In testimony whereof I have affixed my signature in the presence of two subscribing witnesses.
